MOTOR VEHICLE LAMP LENS

Terry R. Henline, Royal Oak, Mich., assignor to General Motors Corporation, Detroit, Mich., a corporation of Delaware

Filed Sept. 26, 1968, Ser. No. 13,729

Term of patent 7 years

Int. Cl. D12—99

U.S. Cl. D48—32

Fig. 4

Fig. 4

FIGURE 1 is a front elevational view of a motor vehicle lamp lens, showing my new design, the faceted lens surface being fragmentarily shown in the center area for convenience of illustration, it being understood that the faceted surface appears throughout said area; FIGURE 2 is a partially sectioned view taken along line 2—2 of FIGURE 1;

FIGURE 3 is a sectional view taken along line 3—3 of FIGURE 1.

FIGURE 4 is a view taken along line 4—4 of FIGURE 1.

I claim:

The ornamental design for a motor vehicle lamp lens, substantially as shown and described.
